W. L. BARRON,
BUTTON CLAMP FOR SEWING MACHINES.
APPLICATION FILED MAY 29, 1919.

Patented May 9, 1922.

WITNESSES:

Mr. Max. Drwell
H. Kornmann

INVENTOR
William L. Barron
BY *Henry J. Miller*
ATTORNEY

UNITED STATES PATENT OFFICE.

WILLIAM L. BARRON, OF NEWARK, NEW JERSEY, ASSIGNOR TO THE SINGER MANUFACTURING COMPANY, A CORPORATION OF NEW JERSEY.

BUTTON CLAMP FOR SEWING MACHINES.

1,415,426.

Specification of Letters Patent.

Patented May 9, 1922.

Application filed May 29, 1919. Serial No. 300,687.

To all whom it may concern:

Be it known that I, WILLIAM L. BARRON, a citizen of the United States, residing at Newark, in the county of Essex and State of New Jersey, have invented certain new and useful Improvements in Button Clamps for Sewing Machines, of which the following is a specification, reference being had therein to the accompanying drawings.

10 This invention relates to a button sewing machine and has for an object to provide an improved button-clamp therefor adapted to securely hold buttons of a large variety of sizes in respect to both diameter and thickness.

15 A further object of the invention is the provision of a button-clamp with simple and readily accessible means for adjusting the clamp-jaws when changing from thick to thin buttons or from large to small buttons, or vice versa.

20 In its preferred form the button-clamp comprises a carrier or supporting bar sustaining a pair of spring-pressed levers whose free ends are directed toward each other and constitute button-clamp jaws having button-gripping faces for engaging the periphery of a button. Positioned between the button-clamp jaws and movable laterally therewith, is a pair of button confining fingers, whose free ends are adjustable along the faces of the button clamp jaws toward and from button-supporting means arranged beneath the clamp-jaws. The button-confining fingers, near their forward ends, are operatively connected with an arm of an adjusting lever, mounted upon the supporting bar, by which the fingers may be shifted toward and from the supporting

25 means, clamping means being provided for retaining the button-confining fingers in adjusted position. Secured upon the carrier or supporting bar is the usual spring-pressed stop-lever which controls the relative adjustment of the clamp-jaws toward and from each other. The adjustments for diameter and thickness of button are independent of one another.

30 In the accompanying drawings, Fig. 1 is a side elevation of the button-clamp. Fig. 2 is a top plan view of the same. Fig. 3 is a bottom plan view omitting the button supporting plate. Fig. 4 is an end elevation of the clamp holding a large button and Fig. 5 is a sectional detail through the

35 bracket for holding the adjusting lever in position.

40 In the present instance, the work-holder is of the well known type disclosed in the patent to J. J. Sullivan, No. 777,564 of December 13, 1904, and it may be applied to the machine disclosed in said patent. It comprises a slide-bar 1 sustaining a work-support in the form of a feed-plate 2 at its forward end. Mounted upon the slide-bar 45 1, at its rearward end is the block 3, a portion only of which is shown in Fig. 1, in which is loosely mounted the downturned extremity of the forwardly projecting button-clamp carrier 4 which is pressed downwardly toward the slide-bar 1 by the usual leaf-spring 5. Suitably mounted upon the carrier 4 are the reciprocably movable button-edge clamping levers 6, 6, formed at their inturned extremities with opposed 50 clamp-jaws 7 having preferably concave button-gripping faces 8 for engaging the periphery of a button 9. As herein shown, these faces are not convergently inclined upwardly as has been common heretofore. Projecting downwardly from the levers 6, 6, are pins 9, 9, which enter the rearwardly converging slots 10, 10, formed in the slide-plate 11 secured to the usual slide-bar 12 sustained beneath the carrier 4 and carrying the 55 stud-screw 13 which projects upwardly through a slot 14 in said carrier and is connected by a spring 15 with the clamp-lifting post 16.

60 The carrier 4 sustains the usual adjustable stop-lever 17 which limits the forward movement of the stud-screw 13 to control the approach of the levers 6, 6, under the action of the spring 15 and plate 11. This lever is pivoted at one end to the carrier 4 by the 65 screw 18 and is formed at its opposite end with a finger-piece 19 and an adjacent segmental slotted portion 20 through which passes the clamp-screw 21 entering the carrier. When the stop-lever is set to space the 70 clamp-jaws 7, 7, a given distance apart, buttons whose diameters are only slightly greater than said given distance may be readily forced between said yielding jaws and into engagement with the usual button 75 centering stop 22 carried by the slide-bar 12.

80 Secured to the under side of the carrier 4 by means of the screw 23 and centering pin 24, is the spring plate 25 whose forward portion is directed beneath the clamp-jaws 7 85 110

to form a support for and engage the bottom-face of the button when it is inserted between the jaws as fully disclosed in the Patent No. 777,564 previously referred to. The supporting plate 25 has laterally extending portions 26, 26, spaced apart to afford a clearance for the fastening stitches which secure the button to the fabric.

Suitably mounted upon pivot-screws 27, 27 entering lugs depending from the rear ends of the clamping levers 6, 6, are the levers 28, 28, whose free ends are directed between and adjacent the inner button-gripping faces 8, 8, of the clamp-jaws 7, 7, and terminate in button-confining fingers 29, 29 adapted to engage the upper face of a button. The levers 28, 28, are perforated intermediate their ends to loosely receive a cross-pin 30 which has a link connection 31 with the arm 32 of the adjusting lever 33 fulcrumed upon the screw-pin 35 passing through the bracket 36 and entering a suitably threaded aperture in the adjusting lever. The bracket 36, which is secured to the carrier 4 by the fastening screws 37, is provided with an arcuate slot 38 to receive the adjusting screw 39 which enters a suitably threaded aperture in the adjusting lever 33, as represented in Fig. 5. It will be observed that the levers 28, 28, being mounted upon the levers 6, 6, move laterally therewith in the adjustment of the clamp-jaws and by means of the adjusting lever 33 they can be moved toward and from the supporting plate 26 independently of the spreading adjustment. By reason of this readily accessible shifting means, while the button clamp-jaws remain in operative position, the button-confining fingers 29 may be set in any desired initial working position or elevation with respect to the button supporting plate, the screw 39 retaining the fingers in such adjusted position to insure their spacing apart from the button supporting plate in readiness for receiving buttons of a given thickness.

In the use of the device, the clamp-jaws 7, 7, are first adjusted to conform approximately with the diameter of the button 6 by setting the stop-lever 17 and after the button has been inserted between the jaws, the button-confining fingers 29, 29 are set to conform with the thickness of the style of button to be handled by lowering them upon the button resting upon the supporting plate 26.

While I have shown and described the preferred embodiment of my invention, it is to be understood that the form and arrangement of its essential elements are susceptible of material modification within the scope of the invention.

Having thus set forth the nature of the invention, what I claim herein is—

65 1. A button-clamp for sewing machines

comprising a carrier, button clamp-jaws sustained by said carrier, button-confining fingers interposed between said jaws, and means readily accessible while the button clamp-jaws remain in operative relation, for shifting the button confining fingers relatively to said jaws. 70

2. A button-clamp for sewing machines, comprising a carrier, button clamp jaws sustained by said carrier, button - supporting means, and button-confining fingers movable laterally with said jaws with means for adjusting their initial position toward and from said supporting means in readiness for the reception of a button. 75

3. A button-clamp for sewing machines, comprising a carrier, button-gripping levers with opposed jaws movably mounted upon said carrier, button - supporting means located beneath said jaws and independent thereof, button - confining fingers also mounted upon said gripping levers, and means for adjusting said fingers toward and from said support. 80

4. A button-clamp for sewing machines, comprising a carrier, opposed button-gripping jaws movably mounted upon said carrier, button-supporting means, button-confining fingers mounted between said jaws for adjustment toward and from said supporting means, and means for maintaining said fingers in adjusted position. 90

5. A button-clamp for sewing machines, comprising a carrier, opposed button gripping jaws mounted upon said carrier, means for simultaneously moving said jaws toward and from each other, button supporting means, button confining fingers also sustained by said carrier, and means for shifting said fingers toward and from the button supporting means and comprising a plurality of connected elements movable together as a unit in performing said shifting action. 100

6. A button-clamp for sewing machines, comprising a carrier, simultaneously movable button clamp-jaws sustained by said carrier, button supporting means also sustained by said carrier independently of said jaws, button confining fingers supported by said carrier, and means readily accessible while the button clamp jaws remain in operative position for shifting the button confining fingers toward and from the button supporting means. 110

7. A button-clamp for sewing machines comprising a carrier, opposed button gripping jaws sustained thereby and connected for reciprocal movement thereon, means for imparting to said jaws button gripping movements, button confining fingers also sustained by said carrier and movable laterally with said jaws, and means for shifting the positions of said fingers relatively to said jaws and transversely of the plane of said button gripping movements. 120

130

8. A button-clamp for sewing machines comprising means for yieldingly gripping the periphery of a button, confining means engaging the opposite faces of the button, 5 and means for adjusting the spacing apart of the second-named means in readiness for receiving buttons of different thicknesses.
9. A button-clamp for sewing machines, comprising a carrier, button-gripping levers 10 mounted upon said carrier and having at their extremities button-gripping faces, button-confining fingers mounted at their rear ends upon the button-gripping levers with their forward ends adjustable across the 15 faces of the button-gripping levers, and means for adjusting the position of said fingers with respect to said button-gripping faces.
10. A button-clamp for sewing machines, 20 comprising a carrier, button-gripping levers mounted upon said carrier, button-supporting means, button-confining fingers movable laterally with said button-gripping levers and an adjusting lever also sustained 25 by said carrier and operatively connected with said button-confining fingers for moving the latter toward and from the button-supporting means.
11. A button-clamp for sewing machines
- comprising a carrier, button-clamping levers mounted upon said carrier and having at their extremities button-gripping faces, button-supporting means independent of said clamping levers, button-confining fingers mounted at their rear ends upon said 30 clamping levers and having their forward ends disposed adjacent said button-gripping faces, a cross pin in operative engagement with said button-confining fingers, and an adjusting lever mounted upon said carrier 35 and operatively connected with said cross pin for moving the button-confining fingers toward and from the supporting means.
12. A button-clamp for sewing machines comprising a carrier, reciprocally movable 40 button edge gripping jaws sustained by said carrier, means entering the space between said edge-gripping jaws for engaging one face of the button, said means being adjustable to any desired working elevation, means 45 for retaining said button-face engaging means rigidly in adjusted position, and means for engaging the other face of the 50 button.

In testimony whereof, I have signed my 55 name to this specification.

WILLIAM L. BARRON.
